UNITED STATES PATENT OFFICE.

CHARLES F. WETZEL, OF SHERWOOD, OREGON.

SPARK PLUG.

Application filed August 31, 1923. Serial No. 660,365.

To all whom it may concern:

Be it known that I, CHARLES F. WETZEL, a citizen of the United States, residing at Sherwood, in the county of Washington and State of Oregon, have invented a new and useful Spark Plug, of which the following is a specification.

This invention relates to spark plugs and aims to provide novel means whereby a plurality of sparks may be produced at the firing end of the plug, to increase the efficiency of the engine of which the spark plug forms a part.

Another important object of the invention is to provide a plug having a plurality of points so that when one point becomes fouled a spark may be provided through the adjacent point.

A still further object of the invention is the provision of means whereby the spark points may be adjusted to insure the proper spark.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a side elevational view disclosing a spark plug constructed in accordance with the invention.

Figure 2 is a front elevational view thereof, a portion of the shell being broken away to disclose the spark points.

Referring to the drawing in detail, the reference character 5 designates the body portion or shell of the spark plug within which is positioned the usual core 6 formed of suitable insulating material, which is held in position by means of the securing nut 7.

Extending through the core 6 is a central electrode 8 which is formed with a threaded portion at its upper end to receive the nut 9, while the lower extremity thereof is threaded to receive the point supporting

member 10. This point supporting member 10 is formed of a length of conductive material curved as clearly shown by Figure 1 of the drawing and provided with a threaded opening to permit the same to be readily positioned over the lower threaded end of the electrode 8.

As shown, the construction of the support 10 is such as to provide a pair of parallel arms 11, the outer arm supporting the point through which the electric energy passes to the stationary spark point 13, which is formed integral with the shell 5 and extended inwardly, the free end thereof lying between the lower end of the electrode 8 and the spark point 12. From the foregoing it will be obvious that due to the construction of the support 10, the spark point 12 may be adjusted towards and away from the stationary spark point 13 to insure the proper spark being made at the sparking end of the plug.

From the foregoing it will be obvious that a plurality of spark points are provided and that should one of the spark points become fouled, the spark will jump between the remaining point of the plug.

I claim:

A spark plug including a shell, a core in the shell, an electrode carried by the core and having threaded portions beyond the ends of the core, a stationary spark point carried by the shell and extending in proximity to the central electrode, a curved supporting member having threaded members adjacent to its ends, one of said threaded openings adapted to accommodate the central electrode, to adjustably support the curved supporting member on the central electrode, a threaded spark point adapted to pass through the opposite threaded opening of the supporting member to adjustably support the last mentioned threaded spark point.

In testimony that I claim the foregoing as my own, I have hereto affixed my signature in the presence of two witnesses.

CHARLES F. WETZEL.
